US00D576492S

(12) **United States Design Patent**
Crawford et al.

(10) **Patent No.:** US D576,492 S
(45) **Date of Patent:** ** *Sep. 9, 2008

(54) **RIGHT SIDE PORTION OF A CONTAINER**

D124,748 S 1/1941 Lloyd

(75) Inventors: **John C. Crawford**, Mahopac, NY (US);
Roland Charriez, Mohegan Lake, NY
(US)

(Continued)

(73) Assignee: **Colgate-Palmolive Company**, New
York, NY (US)

FOREIGN PATENT DOCUMENTS

AU 96326 6/2006

(*) Notice: This patent is subject to a terminal disclaimer.

(Continued)

(**) Term: **14 Years**

Primary Examiner—Stella M. Reid

(21) Appl. No.: **29/278,217**

Assistant Examiner—Elizabeth J Oswecki

(22) Filed: **Mar. 22, 2007**

(74) *Attorney, Agent, or Firm*—Michael J. Wallace

(51) **LOC (8) Cl.** 09-01

CLAIM

(52) **U.S. Cl.** **D9/516; D9/545**

The ornamental design for a right side of a container, as
shown and described.

(58) **Field of Classification Search** D9/516,
D9/522, 530, 537, 540, 543, 545, 549, 571,
D9/544, 575, 500, 502, 505, 687, 688-691;
215/381-385, 396, 398

DESCRIPTION

See application file for complete search history.

FIG. 1 is a perspective view of the right side portion of a
container showing our new design;

(56) **References Cited**

FIG. 2 is a front elevation view thereof.
